E. H. RYERSON

DISH DRAINER

Filed Feb. 29, 1924

FIG. 1

FIG. 2

FIG. 3

INVENTOR.

BY *Eugene H. Ryerson*

John L. Devrey

ATTORNEY.

UNITED STATES PATENT OFFICE.

EUGENE H. RYERSON, OF WOONSOCKET, RHODE ISLAND.

DISH DRAINER.

Application filed February 29, 1924. Serial No. 696,062.

To all whom it may concern:

Be it known that I, EUGENE H. RYERSON, a citizen of the United States, residing at Woonsocket, in the county of Providence and State of Rhode Island, have invented certain new and useful Improvements in Dish Drainers, of which the following is a specification.

My invention relates to a dish drainer, and particularly to that class of dish drainers made of wire, and consisting of a series of longitudinal wire rods, and a series of transverse wire rods, and upright sides, and a wire rod extending around the top, in the usual and well known way.

The object of my invention is to improve upon the construction of the class of drainers above referred to, and more particularly to furnish means, forming a part of and integral with the dish drainer, to hold the dishes in an upright position and separate them from each other.

In my improved construction of the drainer, I extend the side rods above the top rod, to form upwardly extending projections, preferably of loop shape, which extend within the body of the drainer, at the upper part thereof, and form a series of divisions or partitions at the top of the drainer, preferably on each side thereof, with spaces between them to receive the side edge of the dishes, and hold them in a substantially vertical position and separated from each other.

My invention consists in certain novel features of construction of my dish drainer, as will be hereinafter fully described.

Referring to the drawing:—

Fig. 1 is a top or plan view of a drainer, looking in the direction of arrow *a*, Fig. 2.

Fig. 2 is a side view, looking in the direction of arrow *b*, Fig. 1, and,

Fig. 3 is an end view, looking in the direction of arrow *c*, Fig. 1.

In the accompanying drawing, 1 is the main receptacle or compartment of the drainer, to receive the dishes, which is made of open work wire, in the form of a tray, having the top wire or rod 1' extend around the drainer at the upper part thereof, and the vertically extending side rods 2, and end rods 3, and longitudinally extending rods 4, and cross rods 5. Some of the longitudinal rods 4 are provided with upwardly extending *Y* shaped projections 4', see Fig. 2, forming recesses to receive the lower edge of the

dishes, all in the usual and well known way.

I will now describe my improved construction of my drainer.

The rods 2, Fig. 3, forming the sides of the drainer, have their upper ends extend above the top rod 1' of the drainer, and bent over and attached to the top rod of the drainer, as shown in Figs. 2 and 3, to form a series of divisions or partitions 2' on each side of the drainer. The divisions 2' extend above the top rod 1' of the drainer, and within the side top rods of the drainer, and form a series of spaces 2" on each side of the drainer, at the top thereof, to receive the side edge of the dishes placed within the drainer, and in connection with the recesses at the bottom of the drainer, formed by the *Y* shaped projections 4', act to hold the dishes in a substantially upright position, and separated from each other. In case of small dishes, not extending the full width of the drainer, they may be placed at one side of the drainer, and they will be held in a substantially upright position, and separated from each other by the divisions 2' on one side of the drainer, in connection with the recesses at the lower part of the drainer.

It will be understood that the details of construction of my improvements in dish drainer may be varied if desired.

I have particularly referred herein to a drainer for dishes, but my drainer may be used for glass ware, as tumblers, which may be supported upside down on the upper ends of the partitions 2'.

I have shown the divisions or partitions at the top of the drainer, on the sides thereof; if preferred they may be on the ends of the drainer.

Having thus described my invention, what I claim as new and desire to secure by Letters Patent is:—

1. A drainer for dishes, comprising a main receptacle having some of the side rods extend above the top rod of the drainer, to form spaces above the top rod to receive the side edge of the dishes.

2. An improved wire dish drainer, having spaces above the top rod of the drainer, to receive the side edge of the dishes placed in the drainer, said spaces made by the side rods of the drainer extending above and on the inside of the top rod of the drainer.

EUGENE H. RYERSON.
